CORN HARVESTER

Russell A. Hamaker, Rochelle, Ill., assignor to
L. H. Schultz Manufacturing Company, Ro-
chelle, Ill., a corporation of Illinois

Application November 12, 1949, Serial No. 6,004

Term of patent 14 years

(Cl. D40—1)

To all whom it may concern:

Be it known that I, Russell A. Hamaker, a citizen of the United States, residing at Rochelle, in the county of Ogle and State of Illinois, have invented a new, original, and ornamental Design for a Corn Harvester, of which the following is a specification, reference being had to the accompanying drawings, forming part thereof.

In the drawings:

Fig. 1 is a side view of a corn harvester showing my new design;

Fig. 2 is a perspective view, taken from the other side toward the rear; and

Fig. 3 is a front view.

I claim:

The ornamental design for a corn harvester, as shown.

RUSSELL A. HAMAKER.
